Primary Examiner — T Chase Nelson*Assistant Examiner* — Jeff Lenard D Torres(74) *Attorney, Agent, or Firm* — Banner & Witcoff, Ltd.(57) **CLAIM**

The ornamental design for a shoe as shown and described.

DESCRIPTION

FIG. 1 is a front perspective view of a shoe showing my new design;

FIG. 2 is a side view thereof;

FIG. 3 is an opposite side view thereof; and,

FIG. 4 is a top view thereof.

The broken line showing of the interior of the Z-shaped stripe forms no part of the claimed design. The remainder of the shoe shown in a lighter grey photographic depiction forms no part of the claimed design.
